COILABLE MEASURING DEVICE

Frederick A. Volz, New Britain, Conn., assignor to
The Stanley Works, New Britain, Conn., a cor-
poration of Connecticut

Application July 7, 1932, Serial No. 621,220

2 Claims. (Cl. 33—138)

This invention relates, generally, to measuring devices of the type which includes a flexible rule or tape, and resilient means for automatically winding or aiding in winding the tape into coiled form within a suitable casing. The invention, more particularly, relates to the construction of the casing and to the manner in which the inner end of the winding strip is anchored in place.

An aim of the invention is to provide an improved casing comprising two complementary parts which are very simply interlocked against relative rotation, the construction being such that this interlock is obtained without any additional expense.

A further aim of the invention is to provide, in a coilable measuring rule of this type, an improved, simplified and economic arrangement for anchoring the winding strip or blade to the central post or stud within the casing.

Other objects will be in part obvious and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the accompanying drawing, wherein is shown, for illustrative purposes, one embodiment which the present invention may take:

Figure 1 is a side view of the complete device;

Fig. 2 is an inside view of that half of the casing which carries the stud or post, a portion of the winding strip or blade being illustrated;

Fig. 3 is an edge view of the two parts of the casing in slightly spaced apart relation;

Fig. 4 is a view similar to Fig. 2 on an enlarged scale;

Fig. 5 is a sectional view taken through the overlapped portions of the casing, this view being taken substantially on line 5—5 of Fig. 7;

Fig. 6 is a side elevational view of the central stud; and

Fig. 7 is an edge view of a portion of the assembled casing.

Referring to the drawing in detail, the casing, designated generally by the letter A, is of circular form and comprises two cup-shaped members 10 and 11, the open end of one of which is adapted to telescope into the open end of the other. Each of these members is preferably formed of thin metal by stamping out a blank to the desired configuration and then drawing or spinning the blank to cup-shaped form. The member 10 has a side wall 12 and a peripheral cylindrical wall 13,

the marginal edge of which is offset outwardly so as to provide a flange 14 of increased diameter, and an internal seat 15. This flange extends substantially, but not all of the way, around the part 10, there being, between the ends of the flange, a portion 16 which has the same radius as the peripheral wall 13; that is to say, the portion 16 is in the circumference of the wall 13. There is thus provided, at the opposite ends of the flange 14, oppositely facing internal and laterally extending shoulders 17 and 18, respectively. The peripheral wall of the part 10 has a transversely extending notch 19 located between the ends of the flange 14 and opening into the edge of the portion 16. The rear edge of this notch may have an integral and outwardly extending tongue 20.

The other part 11 of the casing has a side wall 25 and a peripheral cylindrical wall 26 of a diameter corresponding to the peripheral wall 13. The cylindrical wall 26 is provided with a stepped notch having an outer portion 27 corresponding in width to the notch 19 and adapted, when the parts are assembled, to form with that notch an entrance opening or slot for the flexible tape, 25 which is designated generally by the letter T. The slot in the part 11 also has an enlarged portion 28 adapted to accommodate the portion 16 of the part 10. The ends of the enlarged notch 28 constitute shoulders 29 and 30 which are adapted to respectively engage the shoulders 17 and 18 when the parts are assembled.

When the parts of the casing are assembled, the marginal portion of the cylindrical wall 26 fits snugly and frictionally within the flange 14 and bottoms against the internal shoulder 15 of the part 10. The enlarged notch 28 accommodates the portion 16 so that relative rotation of the two parts of the casing in either direction is effectively prevented. It will be seen that both parts of the casing may be very cheaply and economically made by merely stamping out a blank and then drawing the blank to form. The enlarged portion of the notch 28 may be cut at the same time that the narrow portion 27 is cut and at no additional expense. The flange 14 may be formed as described during the single drawing operation of the cup-shaped member 10. Thus, the interlock between the parts of the casing preventing those parts from rotating relative to one another in either direction is obtained at no additional expense over what the cost of manufacturing the parts would be without that interlock. The ease and facility with which the two parts of the casing may be assembled are apparent.

Heretofore, it has been the usual practice, in devices of this sort, to anchor the winding blade or strip to the central stud or post by means of a rivet or by providing a transverse slot in the stud and engaging therein the turned over end of the winding strip, both of which arrangements are open to the objection that they entail material expense when it is kept in mind that devices of this sort must be sold within a relatively small margin of profit due to competitive conditions. Also, with these old arrangements, considerable difficulty is experienced in properly attaching the winding strip to the stud. As previously stated, an aim of the present invention is to provide an improved arrangement for anchoring the inner end of the winding strip to the central stud, and which arrangement, while being at least as effective as the old arrangement, is characterized by its simplicity, by its economy in manufacture, and by the ease and facility with which the winding strip may be associated with the stud. This arrangement will now be described.

The central stud or post 35 is suitably anchored to one part of the casing, in the present instance to the part 18 as by a heading operation. This stud may, as usual, have a threaded bore adapted to receive a screw 36 which is employed for holding the two parts of the casing together. This stud, which is of generally cylindrical form, has, at one side, a pressed out wing 37 which may be formed by pinching a portion of the periphery of the stud between a pair of opposed dies and jaws. There is thus formed on the stud a radially disposed longitudinally extending shoulder 38 and a chordal surface 39 disposed generally at right angles thereto. The winding strip or blade is designated generally by the letter B and where the tape comprises a strip of resilient metal having a concavo-convex form so that, when extended, it will automatically assume a rectilinear state or rod-like form, this winding strip may comprise a metal ribbon coiled upon itself and having a tension which is only such as to approximately balance the resistance of friction and the tendency of the measuring strip to resist bending. The inner end of this strip is bent back upon itself so as to form a hook 40, the edge of which is adapted to take in behind and engage the shoulder 38 of the stud. The inner face of the hook rests upon the chordal surface 39. With this arrangement, it will be seen that, to engage the strip with the stud, it is merely necessary to place the hook behind the wing, draw the end of the hook against the shoulder 38, and then wind the strip about the stud. The second convolution of the strip will engage the hooked end thereof and thus hold the hook in engagement with the wing. It will be observed that this arrangement is an extremely simple one, the cost of forming the wing on the stud and the hook

on the winding strip being practically negligible. The assembly of the strip about the stud may be very quickly and easily effected.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. A casing for a coilable measuring device comprising two cup-shaped complementary members each of which has a side wall and a cylindrical peripheral wall, one of said members having a transversely extending notch in its peripheral wall and a radially offset flange at its open end extending around its periphery and terminating short of said notch with ends comprising portions bordering said notch that are inset with respect to said flange, the other of said members having in its peripheral wall an enlarged notch opening into the marginal edge of said member and a narrow notch leading from said larger notch, the peripheral edge of said second member being adapted to engage within the flange of the first member with the edges of the enlarged notch engaging the internal ends of said offset flange, said narrow notch and said first mentioned notch constituting an entrance opening for the measuring tape.

2. A casing for a coilable measuring device comprising two complementary sheet metal cup-shaped members each having an end wall and a generally cylindrical peripheral wall, one of said members having a notch opening into the edge of the member and a radially offset flange at its marginal edge extending around its periphery and terminating short of said notch with ends comprising portions bordering said notch that are inset with respect to said flange so as to provide a pair of internal oppositely facing shoulders to opposite sides of said notch, the other of said members having an end wall and a generally cylindrical wall, the marginal edge of the latter of which is adapted to engage within said flange, the peripheral wall of said second member having a notch with a portion complementary to said first notch and a larger portion at the marginal edge of said member adapted to receive the marginal portion of the peripheral wall of the first member between the ends of said flange.
